UNITED STATES PATENT OFFICE.

THOMAS ORANGE JOHNSON, OF MERIDEN, CONNECTICUT, ASSIGNOR TO HIMSELF AND EDWARD HENRY MUNSON, OF SAME PLACE.

BLAST APPARATUS.

SPECIFICATION forming part of Letters Patent No. 363,294, dated May 17, 1887.

Application filed November 12, 1885. Serial No. 182,585. (No model.)

To all whom it may concern:

Be it known that I, THOMAS ORANGE JOHNSON, a subject of the Queen of Great Britain, residing at Meriden, in the county of New Haven and State of Connecticut, have invented 5 new and useful Improvements in Blast Apparatus, of which the following is a specification.

This invention relates to a blast apparatus 10 in which a reservoir or receiver is combined with a suitable valve for regulating the outflow from said receiver and with a blast-channel.

The object of the invention is to afford facilities 15 for the proper and economical production and application of blasts.

In the accompanying drawings, Figure 1 is a section in the plane $x x$, Fig. 2. Fig. 2 is a section in the plane $y y$, Fig. 1.

Similar letters indicate corresponding parts. 20 In the drawings, the letter A represents the main or supporting frame of the apparatus, which main or supporting frame A can be made of any suitable material—as, for example, wood or iron—and said main or supporting frame can be made of such a shape as to 25 enclose the working parts of the apparatus.

B is a receiver or reservoir, which can be hung or supported in the frame A in any suitable manner and by any suitable means. The 30 outlet C of the receiver B communicates with another outlet, D, and said reservoir or receiver B is provided with a valve, E, for regulating the outflow of material from the receiver B. A secondary valve, $e e$, can act 35 supplementally to the first valve, E.

The secondary valve $e e$ can consist of two plates or wings, which can be slid toward or from one another, so as to leave a less or greater aperture between them or to close the outlet 40 D entirely. By closing one of the plates or wings of the valve $e e$ more than the other the space or outlet between the said wings or plates can be shifted toward one side or the other of the outlet D.

45 On each side of the outflow C are arranged blast-channels I I. A single blast-channel, I, could be employed; but it is preferable to have two blast-channels, I I, as shown in Fig. 1, so that the blast of air, steam, or gas can be directed along each side of exit C. Each blast-

channel I can be provided with a valve, which valves may each consist of a plate, a, which can be slid or moved into the respective blast-channel a greater or less distance, so as to regulate the outflow from the blast-channel. The 55 plates or valves a a, as also the wings or plates of the valves $e e$, can be opened or closed by eccentrics c c, suitably mounted on shafts b d. These shafts b d can be provided with suitable 60 cranks or handles, and by turning the shafts b d the valves a and e can be opened or partially opened and also closed, as desired.

The valve E of the exit C can be conveniently formed by snugly fitting a shaft or roller into the exit-channel C by providing said shaft 65 or roller with a slot, as seen in Fig. 1. By placing the valve E into the position shown in Fig. 1 the maximum outflow of material from the receiver B is obtained. By turning the valve E in one direction or another the outflow can be diminished or entirely shut off, as desired. The valve E can be operated by a 70 suitable crank or handle, F.

The blast-channels I I communicate by ducts or conduits H H with a tube or channel, G, 75 into which air or gas can be forced or blown by any suitable apparatus—as, for example, a fan-blower. If, for example, the receiver or reservoir B is supplied with sand, it flows through the exits C D, and is thrown or impelled by the blast from the blast-channels I I. 80 against any object suitably placed near the exit D.

The object or objects to be subjected to the blast can be placed on a suitable carrying 85 mechanism—as, for example, a carrier or tray, M. The carrier or tray M can rest upon rollers K L, and said carrier or tray M can be inserted through the opening o in the frame A, near the arrow 1 in Fig. 1, and said tray can 90 be moved at suitable speed through the apparatus in the direction of said arrow 1, and drawn out of the apparatus through another opening, o, corresponding to the first-named opening o. The desired motion can be communicated to the carrier or tray M by placing said carrier M upon rollers K L, and causing 95 said rollers to revolve at a suitable speed and in the proper direction. By providing the tray M with a perforated bottom through 100

which sand or small bodies can escape, accumulation of such sand or small bodies upon the carrier M is prevented.

In the example shown in the drawings, it is only necessary to communicate motion to the rollers K K K, which will be sufficient to move carrier M along, the rollers L serving merely as supporting-rollers. The axle N of the roller K can receive motion from a gear-wheel, O, to which motion is communicated from the shaft Q, mounted in suitable bearings, Z. The shaft Q can be actuated by bevel-gears R S, which bevel-gears receive motion from the main shaft T, to which motion can be communicated by a suitable pulley and belt, U, connecting with any suitable motive power.

The motion of the shaft N causes the roller K on said shaft N to turn, and by suitable pulleys, W V V, and belts Y X (shown in dotted lines in Fig. 1) the remaining rollers K K can receive a revolving motion. The bearings for the axles of the rollers K L can be formed in the frame A, or in any suitable braces or bars in said support A.

25 When the material employed in the blast—as, for example, sand—has passed out from the carrier M, it falls on the ridge or inclined bottom r of the apparatus, and is led by the inclined ways t to the collecting space or spaces 30 s. From these spaces s the sand or other material can be returned to the receiver B, to be used over again, thereby avoiding loss or waste.

A suitable feeding mechanism can be employed to supply sand or material automatically to the receiver B. As shown in the drawings, said feeding mechanism can consist of belts or chains i, provided with suitable buckets or scoops, k. As the belts or chains i revolve in the directions of the arrows shown on said belts or chains, the buckets k gather up the sand or material from the spaces s and throw it into the chutes l. These chutes l, as shown in Fig. 2, can project from the sides of 45 the receiver B into the paths of the buckets k, and the material passing from the buckets k into the chutes l is led into the receiver B.

Motion can be communicated to the belts or chains i by causing said belts or chains i to 50 pass over pulleys h on the main shaft T, which main shaft can be revolved by the belt U, as already mentioned. Suitable pulleys, f, can also be mounted on a shaft, g, at suitable positions in the apparatus, and said belts or chains

55 i can be caused to pass over said pulleys f. The belts or chains i can also be led over guide-rollers m, to prevent said chains or belts i from coming into improper contact with any part of the device. This apparatus will be found 60 very useful, for example, in the cleaning of castings. It is known that when such articles as metal castings come from the molds, there adheres to such castings an amount of sand. By placing such castings upon the carrier M 65 and allowing the same to travel through the apparatus the sand-blast from the outflow or spout D will clean such castings. Of course,

I do not confine myself to the use of the apparatus for the purpose of cleaning castings, as said apparatus may be useful for other purposes—as, for example, for sanding glass. It is known that when glass is subjected to a sand-blast it can be made translucent, or its transparency more or less destroyed, and also by a proper application of a sand-blast ornamental figures can be produced upon glass. By placing glass or objects made of glass upon the carrier M and passing them through the apparatus a proper application of the blast can be obtained. In place of a sand-blast, the apparatus may be used to generate a blast of any other suitable material—as, for example, emery, or a mixture of sand and emery, or any other suitable material.

While the blast is in operation, the openings 85 o o are closed by doors or covers n n, which can be swung upon pivots or hinges, and which can be held open when desired by suitable hooks and chains, p p, or by other suitable means.

90 The apparatus can be closed by a cover or hood, u, provided with a waste pipe or outlet, v, for carrying off dust and foreign matter or impurities.

The receiver or reservoir B, as also the walls 95 of the ducts H H, blast-channels I I, and exits C D, can be formed of metal or other suitable material. I have found it convenient to rest the receiver B upon the walls of the ducts H, so that upon the removal of the hood or dome 100 u the receiver B can be lifted out of the apparatus for cleaning or repairing. For this purpose the pulleys h will first have to be loosened and the main shaft T removed from the apparatus. The walls of the blast-channels 105 I I can be made to rest on a brace or braces, A', or upon any suitable support or part of the frame A.

In order to prevent the rollers K L and the ridge or inclined bottom r from being injured 110 by the impact of the sand or material from the blast, a covering of rubber or other soft or yielding material should be applied.

In the drawings, Fig. 2, the ridge or bottom r is shown as being covered with rubber or yielding material, and by making the rollers K L of rubber or other soft or yielding material said rollers K L will last much longer than if made of metal or hard material, as such hard material is liable to be cut away or worn 120 by the impact of sand.

In order to enable the progress of the work to be observed, suitable sight-openings can be made in the frame A, which sight-openings can be closed by sheets or panes, q, of some 125 suitable transparent material—as, for example, isinglass, mica, or glass.

While the apparatus is in use the flow of sand will be controlled by properly manipulating the valve E, and the force of the blast 130 will be controlled through the valves a a. If it is desired to cut off the sand-blast momentarily without closing the valves E and a, that effect can be produced by closing the valves e

e in the outlet *D*. Any portion of the article acted on can thus be exempted from the action of the sand-blast, as such article is passed beneath the outlet of the blast.

5. What I claim as new, and desire to secure by Letters Patent, is—

1. The combination, with the exterior casing, *A*, having the hood *u* and waste-pipe *v*, of the reservoir or receiver *B*, having discharge-nozzle *C* and valve *E*, the surrounding blast-channels *I*, nozzle *D*, air-ducts *H*, supply-pipe *G*, and valves *a a e e*, and means, substantially as shown, for presenting and moving articles beneath the nozzle *D*, as and 15 for the purpose herein set forth.

2. In a blast apparatus, the combination of the rubber-covered rollers, means for rotating the same, the perforated tray resting loosely upon said rollers and moved thereby, with the casing *A*, and the blast apparatus and discharging devices for the abrading material arranged above the movable perforated tray, substantially as herein set forth. 20

In testimony whereof I have hereunto set my hand and seal in the presence of two subscribing witnesses. 25
